UNITED STATES PATENT OFFICE.

EDWARD R. THIELER, OF HOBOKEN, NEW JERSEY.

DESIGN FOR A JUG OR SIMILAR ARTICLE.

44,672.

Specification for Design. Patented Sept. 16, 1913.

Application filed June 19, 1913. Serial No. 774,698. Term of patent 7 years.

To all whom it may concern:

Be it known that I, EDWARD R. THIELER, a citizen of the United States, residing at Hoboken, in the county of Hudson and State of New Jersey, have invented a new, original, and ornamental Design for Jugs or Similar Articles, of which the following is a specification, reference being had to the accompanying drawing, forming a part thereof.

In the drawing, Figure 1 shows a side elevation of a jug showing my design and Fig. 2 is a front elevation thereof.

I claim—

The ornamental design for a jug or similar article as shown.

EDWARD R. THIELER.

Witnesses:

HUGO MOCK,
ADOLPH L. MOCK.
